United States Patent Office

Des. 204,281
Patented Apr. 5, 1966

204,281

STILT

Peter F. Phaneuf, Pearl St., Southboro, Mass.

Filed May 17, 1965, Ser. No. 85,307

Term of patent 3½ years

(Cl. D34—14)

FIG. 1

FIG. 2

FIG. 3

FIG. 1 is a perspective view of a stilt showing my new design;

FIG. 2 is a view in front elevation thereof, and

FIG. 3 is a view looking in the direction of arrow 3 in FIG. 2.

I claim:

The ornamental design for a stilt, as shown.
